UNITED STATES PATENT OFFICE.

CHARLES CLEMENTS, OF BOSTON, MASSACHUSETTS.

DESIGN FOR AN ENVELOP, WRITING-PAPER, CARD, OR SIMILAR ARTICLE OF STATIONERY.

44,124.

Specification for Design.

Patented June 3, 1913.

Application filed February 7, 1913. Serial No. 746,966. Term of patent 14 years.

To all whom it may concern:

Be it known that I, CHARLES CLEMENTS, a citizen of the United States, residing at Boston, in the county of Suffolk and State of Massachusetts, have invented a new, original, and ornamental Design for Envelops, Writing-Paper, Cards, or Similar Articles of Stationery, of which the following is a specification, reference being had to the accompanying drawing, forming part thereof.

The figure is a plan view of an envelop showing my new design.

I claim:

The ornamental design for an envelop, writing paper, card or similar article of stationery as shown.

Signed by me at Boston, Massachusetts, this 4th day of February, 1913.

CHARLES CLEMENTS.
